CONTINUOUS ELECTRIC OUTLET UNIT

Joseph A. Messing and Elwood T. Platz, Detroit, and Clarence H. Bock, Royal Oak, Mich., assignors to BullDog Electric Products Co., Detroit, Mich., a corporation of West Virginia

Application March 3, 1954, Serial No. 29,305

Term of patent 14 years

(Cl. D26—1)

Fig. 1 is a top plan view of a continuous electric outlet unit, showing our new design.

Fig. 2 is a front elevational view.

Fig. 3 is a cross-sectional view on line 3—3 of Fig. 2.

Fig. 4 is a cross-sectional view on line 4—4 of Fig. 2.

The dominant features of our design reside in the portions shown in full lines.

We claim:

The ornamental design for a continuous electric outlet unit, substantially as shown and described.
